United States Patent

Des. 235,964

Patented July 22, 1975

235,964

ORANGE PEELER

Antonio R. Lovato and Victoria C. Lovato, Los Angeles,
Calif., assignors to Idex Corporation, Sherman Oaks,
Calif.

Filed May 6, 1974, Ser. No. 467,302

Term of patent 14 years

Int. Cl. D7—04

U.S. Cl. D7—147

FIG. 1 is a perspective view of an orange peeler, showing our new design;

FIG. 2 is a side elevational view thereof;

FIG. 3 is a bottom plan view thereof;

FIG. 4 is a top plan view thereof;

FIG. 5 is an end view thereof as seen from the right of FIG. 2; and

FIG. 6 is an end view thereof as seen from the left of FIG. 2.

We claim:

The ornamental design for an orange peeler, substantially as shown.
